HARDWARE FOR CABINETS OR THE LIKE

La Verne E. Clayton, Rockford, Ill., assignor to
Amerock Corporation, Rockford, Ill.

Filed May 26, 1969, Ser. No. 17,349

Term of patent 14 years

Int. Cl. D8—03

U.S. Cl. D8—166

FIG. 1 is a front view of hardware for cabinets or the like wherein my design is embodied in a pull.

FIG. 2 is a side view of the pull as seen from the right of FIG. 1.

FIG. 3 is a sectional view taken along the line 3—3 in FIG. 1.

FIG. 4 is a top view of the pull.

FIG. 5 is an enlarged sectional view taken along the line 5—5 in FIG. 1.

FIG. 6 is an enlarged sectional view taken along the line 6—6 in FIG. 1.

FIG. 7 is a front view of hardware for cabinets or the like wherein my design is embodied in an escutcheon plate.

FIG. 8 is a side view of the plate as seen from the right of FIG. 7.

FIG. 9 is a sectional view taken along the line 9—9 in FIG. 7.

FIG. 10 is a top view of the plate.

FIG. 11 is an enlarged sectional view taken along the line 11—11 in FIG. 7.

FIG. 12 is an enlarged sectional view taken along the line 12—12 in FIG. 7.

I claim:

The ornamental design for hardware for cabinets or the like, as shown and described.
